CLAIM

The ornamental design for a knee sleeve, as shown and described.

DESCRIPTION

FIG. 1 is a front perspective view of a knee sleeve of the present invention showing my design.

FIG. 2 is a front side elevation view thereof;

FIG. 3 is back side elevation view thereof;

FIG. 4 is a side elevation view thereof;

FIG. 5 is another side elevation view thereof;

FIG. 6 is a top plan view thereof;

FIG. 7 is a bottom plan view thereof; and,

FIG. 8 is a perspective view of FIG. 1 in use.

The broken lines in the drawings are for the purpose of illustrating stitching and form no part of the claim. The broken lines showing a human leg in FIG. 8 are for the purpose of illustrating environment and forms no part of the claim.
